CLAIM

The ornamental design for a crossmember for vehicle, as shown.

DESCRIPTION

FIG. 1 is a top front perspective view of a crossmember for vehicle showing my new design;

FIG. 2 is a bottom front perspective view thereof;

FIG. 3 is a top rear perspective view thereof;

FIG. 4 is a bottom rear perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The broken lines showing portions of the crossmember for vehicle form no part of the claimed design.
